UNITED STATES PATENT OFFICE.

THEODORE SCHIDORSKY AND JACOB BARASHICK, OF NEW YORK, N. Y.

DOOR ATTACHMENT.

1,088,300.

Specification of Letters Patent. Patented Feb. 24, 1914.

Application filed July 22, 1912. Serial No. 780,530.

To all whom it may concern:

Be it known that we, THEODORE SCHIDORSKY and JACOB BARASHICK, citizens of the United States, residing, respectively, at 5 New York city, in the county of Bronx and State of New York, and at New York city, in the county of New York and State of New York, have invented certain new and useful Improvements in Door Attachments, 10 of which the following is a full, clear, and exact specification.

This invention relates to door attachments, particularly devices whereby a person seeking admittance may be viewed from 15 without opening the door.

One object of the present invention is to provide a device of this character which may be attached to a door of substantially any thickness found in practice.

20 Another object is to provide means for attaching the device from within, so that the same may not be tampered with by any unauthorized person without.

A further object is to provide means 25 whereby the transparent window may be readily removed by the person within the house in case he should desire to communicate with the person desiring admittance before allowing him to enter the house.

30 Still further objects and advantages will more fully appear from the detailed description and the features of novelty will be particularly pointed out in the claim.

In the drawing illustrating this invention, 35 Figure 1 is an elevation of our improved device viewed from the exterior of the door, a fragment only of the latter being shown. Fig. 2 is an elevation of the device viewed from the interior of the door. Fig. 3 is an 40 elevation corresponding to that in Fig. 2, with the small door or wicket open. Fig. 4 is a section partly broken away to illustrate the interior construction. Fig. 5 is a 45 sectional view illustrating a modified form containing a spring catch for holding the removable window. Fig. 6 is a further modified form in which the wicket is mounted to swing upon a horizontal instead of a vertical axis. Fig. 7 is a detail view illustrating the 50 frame with the adjustable straps.

The device comprises essentially a frame 55 passing through an aperture in a door from the exterior thereof, this frame being provided with adjustable straps extending through the door and fastened at the in-

terior thereof; a removable window telescoping within the frame provided with means for holding the same in adjusted position; and a small door or wicket which may be opened from within.

Referring in detail to the drawings, the frame consists preferably of an annular plate 10, having a tubular extension 11 projecting therefrom and entering the aperture from the exterior of the door. Extending from this tubular portion 11 are straps 12 formed of sheet metal or some other easily bent material. The ends of these straps may be bent over at the interior and fastened to the interior of the door by suitable attaching means such as screws 13, passing through perforations 14 formed adjacent the ends of the straps. As the latter may be readily bent, it will be seen that they can be made to fit any thickness of door. A suitable frame 15 may also be provided at the interior of the door, this frame having a tubular extension 16 fitting the interior of the aperture and disposed in substantial alignment with the tubular portion 11 of the exterior frame. The frame 15 may be fastened by suitable fastening means such as screws 17, passing into the panel of the door. A door or wicket 18 is hinged to the frame 15 and suitably latched thereto by a latch 19.

The aperture is normally closed at the exterior thereof by a window 20 mounted within a frame consisting of a tube 21 telescoping within the tubes 11 and 16, and provided with an inwardly extending annular rim 12 against which the window abuts, the latter being held firmly in place by a split collar 23 which is suitably fastened to the interior of this tube. The latter abuts against an inwardly extending annular shoulder or rim 25, forming an extension of the plate 10, past the tubular portion 11. The tube 21 may be clamped in position by suitable means such as a set screw 26 threaded in a boss 27, formed at the interior of the tube. Thus, when the person within desires to observe the person seeking admittance, he opens the wicket 18, and if he is still not satisfied, he may unclamp the tube 21 by unscrewing the set screw and remove the same, so as to leave the aperture free for communication. Then the tube 21 may be replaced and the wicket closed, restoring the device to normal position. Preferably, a mirror 28 may be framed in

the interior of the wicket 18, so as to enhance the ornamental appearance of the device when viewed from without.

In the modified form illustrated in Fig. 5, 5 the clamping device consists of a spring 30 which may be struck out of the body of the tube 21. Thus, the latter can be removed by merely grasping the upturned portion 31 of the spring 30 to release the same from 10 its abutment with a suitable projection such as the edge of the tube 16.

In the modification illustrated in Fig. 6, 15 the wicket 32, instead of swinging upon a vertical axis or hinge as in the other forms of our invention, is pivoted to swing about a horizontal pivot 33 and is formed with a hooked projection 34 which itself constitutes the latch for the wicket. If desired, 20 a name plate 35 may be attached to the exterior plate 10, thus adding to the ornamental appearance of the device.

It will thus be seen that we have provided 25 an observation device of this character which cannot be unfastened from the exterior of the door, which is adjustable to any

thickness of door and provided with a window removable from within, which enables a person within to readily communicate with the person desiring admittance in case the observation does not satisfactorily 30 settle the identity of the person.

Having thus described our invention, we claim as new and desire to secure by Letters Patent:

In a device of the character described, a 35 frame having a tubular extension adapted to pass into the interior of an aperture in the door, means for fastening the frame to the door, a tube telescoping within the tubular extension, a window within the tube, 40 and means for clamping the tube permitting easy removal of the same from the aperture by a person within.

In testimony whereof, we affix our signatures, in presence of two witnesses,

THEODORE SCHIDORSKY,
JACOB BARASHICK.

Witnesses:
